SUPPORT STAND FOR DISPLAYING ORNAMENTS

Arthur E. Court, 601 Ortega St.,
San Francisco, Calif. 94122

Filed Aug. 9, 1968, Ser. No. 13,074

Term of patent 14 years

Int. Cl. D6—01

U.S. Cl. D33—17

FIG. 1 is a perspective view of a support stand for displaying ornaments embodying my new design.

FIG. 2 is a top plan view thereof.

FIG. 3 is a side elevational view thereof.

FIG. 4 is a cross-sectional view thereof substantially along line 4—4 of FIG. 3.

FIG. 5 is a bottom plan view thereof.

I claim:

The ornamental design for a support stand for displaying ornaments, substantially as shown.
